ASH TRAY

Gustav A. Carlson, Chicago, Ill., assignor to The
Boye Needle Company, Chicago, Ill., a corpora-
tion of Illinois

Application March 28, 1938, Serial No. 198,592

7 Claims. (Cl. 131—240)

This invention relates to an ash tray. While the invention is described particularly in connection with cigarettes, it will be understood that the device is applicable for cigars, etc.

An object of the invention is to provide an ash tray of simple construction which serves to support the cigarette in a secure manner whereby "sweating" of the cigarette is prevented and whereby the ashes are prevented from coming in contact with the table or other support. A further object is to provide an ash tray which rests firmly upon a table or other support and yet which may be grasped easily and handled without contacting the ashes carried by the tray. A further object is to provide an ash tray of simple sturdy construction whereby cigarettes may be supported at various stepped positions so as to maintain the cigarette, as it is consumed, with the burning portion thereof over the bowl. Other specific objects and advantages will appear as the specification proceeds.

The invention is illustrated, in a preferred embodiment, by the accompanying drawings, in which—

Figure 1 is a plan view of an ash tray embodying my invention; Fig. 2, a longitudinal sectional view, the section being taken as indicated at line 2 of Fig. 1; Fig. 3, a broken detailed sectional view, the section being taken as indicated at line 3 of Fig. 1; Fig. 4, a plan view of a modified form of ash tray; Fig. 5, a plan view of a modified form of ash tray embodying my invention; Fig. 6, a sectional view of the structure shown in Fig. 5, the section being taken as indicated at line 6 of Fig. 5; Fig. 7, a plan view of a structure similar to that shown in Fig. 5, the raised projections being eliminated; and Fig. 8, a plan view of a modified form of structure embodying my invention.

In the illustration given in Figs. 1 to 3 inclusive, 10 designates an ash bowl provided with a circular rim portion 11. Extending from one side of the bowl is a downwardly inclined wall 12 provided at its lower end with an upwardly and slightly outwardly inclined ledge 13. As shown more clearly in Fig. 3, a groove or channel 14 is formed in the wall 12, the channel opening directly into the bowl 10. The groove or channel terminates at 15, a point spaced a short distance from the flange 13.

Associated with the channel 14 are a pair of inclined ribs 16 which spread outwardly toward the rim 11 of the bowl, and at their lower enlarged ends almost converge within the channel 14. The ribs 16 serve the double function of

guiding a cigarette into the channel 14 and also maintaining it slightly above the channel bed whereby air is permitted to circulate freely below the cigarette and thus prevent the sweating or moisture condensation which would otherwise occur and which would tend to extinguish the cigarette. The tray also prevents the lighted cigarette from rolling off and burning the table, rug, etc.

In the ash trays now in use, it is found that 10 where the cigarette lies within a saddle or groove so that air is excluded entirely from the underside thereof, there is a formation of a liquid at that point which stains the cigarette and renders it unsatisfactory. I have found that this can be 15 eliminated by providing means within the channel whereby the cigarette is supported at several spaced points so that air freely circulates about the underside of the cigarette.

The inclined ribs 16 also serve the purpose of 20 enabling the cigarette to be shifted rapidly toward the bowl as it is consumed so that the burning portion of the cigarette rests over the bowl.

The structure shown in Fig. 4 is identical with that shown in Fig. 1 except that the lower portion 25 of the groove 14 is eliminated. In this structure, the ribs 16 terminate substantially at the bottom of the channel. Should the cigarette burn to the point where it will become unbalanced and tilt downwardly, it falls against the ledge 13 and is 30 prevented from coming in contact with the table or other support.

In the structure shown in Figs. 5 and 6, the wall 12^a is provided with a channel 17 which has a stepped bottom 18. Adjacent each of the steps 35 just below them are the upwardly extending projections or knobs 19. The steps enable the cigarette to be shifted toward the bowl as it becomes shorter, thus maintaining the burning end of the cigarette always over the bowl. The spaced projections 19 maintain the cigarette out of contact with the bottom of the channel and thus prevent sweating, etc.

The structure shown in Fig. 7 is identical with that shown in Fig. 5 except that the projections 45 19 are omitted.

In the structure shown in Fig. 8, the laterally extending wall 12^b is annular and completely encircles the bowl 10^a. The channels 20 communicating with the bowl are provided with 50 raised projections 21 of the type illustrated in Fig. 5. At a point intermediate adjacent pairs of channels 20 are spear head shaped openings 22. The downwardly inclined walls 12^b are provided, as in the case of the other structures, with 55

an upwardly and outwardly inclined wall 13^b. The structure shown in Fig. 8 is identical with that shown in the preceding figures with the exception that the wall 12^b extends all the way around the bowl and the channels 20 are provided with projections 21 only and further in the respect that openings 22 are formed between each adjacent pair of channels 20.

In all of the structures illustrated, it will be observed that the tray can be readily grasped for handling the same without bringing the fingers into contact with the ashes of the partially consumed cigarettes. The bottom of the bowl rests upon the support and at a spaced distance therefrom, the lower end of the wall 12, 12^a or 12^b resting upon the support. Between these points is a raised portion permitting the fingers to readily grasp the tray at a point between the bowl and the ledge 13 or 13^b. In the structure shown in Figs. 1 to 7 inclusive, the fingers extend readily around the concave central portion of the downwardly inclined wall, while in the structure shown in Fig. 8 the fingers may be extended through adjacent openings 22 to move the tray. In each and all of the structures, means are provided for maintaining the cigarette above the bottom of the channel or support whereby air circulates thereunder, such means also permitting the cigarette to be maintained at a point in the channel upon which it is placed, the raised projections, steps or ribs serving as a means for locking or maintaining the cigarette at such points with the burning portion of the cigarette over the bowl.

While in the foregoing specification, I have set forth certain details of construction, it will be obvious that such details may be modified considerably in shape, number and form without departing from the spirit of my invention.

The foregoing detailed description has been given for clearness of understanding only, and no unnecessary limitations should be understood therefrom, but the appended claims should be construed as broadly as permissible, in view of the prior art.

I claim:

1. An ash tray of the character set forth, comprising: a bowl and a wall extending downwardly and outwardly from said bowl, said wall being provided at its outer edge with an upwardly directed ledge, said wall being also provided with a cigarette channel communicating with said bowl and providing step means for supporting

cigarettes of different lengths so that the burning ends are maintained above said bowl.

2. A cigarette tray of the character set forth, comprising: a bowl, an integral wall extending laterally and downwardly therefrom and provided with an upwardly turned bottom edge, said wall being provided with a channel and having means adapted to support cigarettes of different lengths with their burning ends over said bowl.

3. A cigarette tray of the character set forth, comprising: a bowl, an integral wall extending laterally and downwardly therefrom and provided with an upwardly turned bottom edge, said wall being provided with a channel and providing steps adapted to support cigarettes of different lengths with their burning ends over said bowl, said channel being provided with raised spaced projections for supporting a cigarette above the bottom thereof.

4. A cigarette tray of the character set forth, comprising: a bowl having an integral laterally extending wall equipped at its lower end with an upturned edge, said wall providing steps for supporting cigarettes of different lengths with the burning portion thereof over the bowl.

5. An ash tray comprising: a bowl equipped with an annular downwardly inclined wall extending laterally therefrom and having a circular upturned edge, channels formed in said wall and communicating with said bowl, said wall being provided with finger openings between said channels and provided with spaced means for maintaining a cigarette above the bottom thereof.

6. An ash tray of the character set forth, comprising: a central bowl, an annular wall formed integrally therewith and extending downwardly therefrom, channels formed in said wall and communicating with said bowl, said wall having an upwardly turned outer edge, spaced means for supporting a cigarette above said wall and out of contact therewith, and finger openings provided between said channels.

7. An ash tray of the character set forth, comprising: a bowl and a wall extending downwardly and outwardly from said bowl, said wall having at its outer edge an upwardly directed ledge, said wall having at least one cigarette channel communicating with said bowl and providing steps for supporting cigarettes of different lengths so that the burning ends are maintained above said bowl.

GUSTAV A. CARLSON.
